UNITED STATES PATENT OFFICE

2,555,503

TRESTLE CLAMP

Paul L. Morton, Long Beach, Calif.

Application January 28, 1949, Serial No. 73,247

1 Claim. (Cl. 304—5)

1

This invention relates to an all purpose clamp for the purpose of mounting and holding the legs of a sawhorse or other supports, such as, a rack, a hoist frame, and the like.

An object of my invention is to provide a simple, inexpensive and effective clamp, which is simple to manufacture and which will effectively hold the legs of a sawhorse, and the like, in an effective manner.

A feature of my invention is to provide a novel all purpose clamp, which can be easily fabricated to hold wooden timbers, such as legs of a sawhorse.

Other objects, advantages and features of invention may appear from the accompanying drawing, the subjoined detailed description and the appended claim.

In the drawing:

Figure 1 is a side elevation of my clamp.

Figure 2 is an end view of the same.

Figure 3 is a perspective view of one side of the clamp.

Figure 4 is a sectional view taken on line 4—4 of Figure 2.

Referring more particularly to the drawing, my clamp consists of two complementary members, **1** and **2**. These members are each formed of a suitable weight of metal and since they are substantially identical, only one will be described in detail.

Each half of the clamp consists of a U-shaped strip of metal, which is stamped from a plate sheet and then bent into a substantial U shape, as shown in Figure 3. A pair of ears **3** and **4** are integrally formed in the sheet of metal and these ears provide a means to attach the sections **1** and **2** together. A bolt or rivet **5** and **6** extends through the ears **3** and **4** respectively, thus securing the parts of the clamp together.

A lip **7** is bent horizontally across the top of the clamp sections **1** and **2**, substantially as shown, and this lip acts as a stop for the leg timber **8** and to prevent the leg from moving upwardly through the clamp. A wall **9** is welded

2

or otherwise fixedly secured in the U shape structure of the clamp section **1** and acts as a side wall to support and confine the timber **8**. The inwardly bent portions of the clamp section **1** are formed with teeth **10** to engage and grip the horizontal timber **11**, which is found in the usual sawhorse. A bracket **12** extends between the legs of the sawhorse, or the like, to spread these legs the proper amount and to thus cause the teeth **10** to sink into the horizontal timber **11**.

The ears **3** and **4** are each cut with a flat upper horizontal surface **13** and **14**, which serve as a recess to conform to the shape of the horizontal timber **11**.

Having described my invention, I claim:

A clamp for sawhorses and the like, comprising a pair of complementary clamp members, each member consisting of integrally formed side and outer walls, a second wall spaced from the outer wall and substantially parallel thereto and fixedly mounted between the side walls whereby a socket is formed to receive the end of a supporting member, an ear formed on each of the said walls of each clamp member, a rivet pin extending through the ears to hingedly secure the clamp member together, a stop lip formed at the top of said outer wall, said lip being bent at right angles and extending towards said second wall to act as a stop for the supporting member, and teeth formed on the inner edge of each of the sides of the clamp.

PAUL L. MORTON.
